Specification for Design.

Patented Mar. 4, 1919.

Application filed June 13, 1917. Serial No. 174,627. Term of patent 3½ years.

To all whom it may concern:

Be it known that I, JOHN M. FISHER, a citizen of the United States, residing at the city of Attleboro, county of Bristol, State of Massachusetts, have invented a new, original, and ornamental Design for a Bracelet, Watch-Fob, or Vest-Chain, of which the following is a specification, reference being had to the accompanying drawing, forming part thereof.

The figure is a plan view of a bracelet in extended position, illustrating my new design.

I claim:

The ornamental design for a bracelet, watch fob, or vest chain as shown.

JOHN M. FISHER.
